E. E. ARNOLD
PROCESS FOR THE MANUFACTURE OF SODIUM BICARBONATE AND THE
PRODUCTION OF NITROGEN
Filed Oct. 21, 1924

Inventor,
Edward F. Arnold
By Percy H. Plant.
Attorney.

UNITED STATES PATENT OFFICE.

EDWARD E. ARNOLD, OF COVENTRY, RHODE ISLAND, ASSIGNOR TO THE NITROGEN CORPORATION, OF PROVIDENCE, RHODE ISLAND, A CORPORATION OF RHODE ISLAND.

PROCESS FOR THE MANUFACTURE OF SODIUM BICARBONATE AND THE PRODUCTION OF NITROGEN.

Application filed October 21, 1924. Serial No. 744,922.

This invention relates to an improved process for the manufacture of sodium bicarbonate and the production of nitrogen, which is particularly applicable for use in connection with the manufacture of iron and steel, but is not limited to this application as it can be applied to any industry where large quantities of carbonaceous fuel is used in close proximity to a salt supply.

10 In the manufacture of iron and steel from the ores in accordance with present methods of operation, the ores are first smelted in a blast furnace to obtain crude iron which may be further treated by various methods, such, 15 for example, as by purification with an air blast in a Bessemer converter, to remove a suitable portion of the carbon and form steel. It is the practice in carrying out the above process to place the ore together with coal 20 or coke and a suitable flux in the blast furnace and after igniting the mass at the base, force a blast of air therethrough to reduce the ore and obtain the same in a molten form while the air forced into the base of 25 the furnace is changed in part to form a gaseous mixture which is withdrawn from the top thereof and utilized as a fuel in stoves or gas engines whereby the unconsumed heating elements of the gases may be 30 utilized most completely.

The composition of the gases as they emerge through a suitable pipe at the top of the blast furnace is represented as made up of the following constituents in approximately the proportions indicated, although it is to be understood that these proportions vary at different times under different conditions and varying methods of operation; nitrogen 60%, carbon dioxide 15%, carbon monoxide 23% and hydrogen 2%. The bases issuing from the furnace may be treated to remove dust and certain foreign materials before being conducted to stoves, gas engines or other suitable furnaces where they are 40 burned with the addition of a sufficient quantity of air to furnish the requisite oxygen for combining with the carbon monoxide and hydrogen content of the gases whereby the heat energy of the gases may be conserved and used. It will be seen from the above 50 that if a proper quantity of air is burned with the gases to provide oxygen for the complete combustion of the carbon monoxide and hydrogen content thereof the resulting gases emerging from the stoves or heaters 55 will be composed of approximately 23 or 24 percent of carbon dioxide while the remaining 76 or 77% will be practically all nitrogen mixed with a small amount of water vapor.

It is the main object of the present invention to utilize the gas mixture thus obtained for the formation of sodium bicarbonate and at the same time eliminate the carbon dioxide from the mixture to provide a convenient 65 means for obtaining substantially pure nitrogen gas in large quantities. The nitrogen thus obtained may be advantageously employed in various processes for the fixation of nitrogen and I may employ it for 70 this purpose as an additional step of the present process. As illustrative of one method by which the nitrogen thus produced may be employed in the fixation of nitrogen I have shown and described its use in a 75 Bessemer converter or like appliance wherein the nitrogen acts upon carbon in the presence of the molten metal to produce carbon-nitrogen compounds. It is to be understood, however, that this particular manner of 80 utilizing the nitrogen in the formation of nitrogen compounds is merely illustrative of one method of operation and that my invention also comprehends the use of the nitrogen produced in forming alkali metal cyanides, 85 ammonia or other nitrogen compounds either by treating an alkali carbonate, carbide or other salt and carbon with the nitrogen or by directly uniting the nitrogen with hydrogen synthetically or by utilizing any other suitable 90 nitrogen fixation process. Thus the double purpose is accomplished of obtaining large quantities of carbon dioxide for the formation of sodium bicarbonate and at the same time large quantities of nitrogen substantially uncontaminated by extraneous 95

gases, the nitrogen thus obtained being conveniently located for use in the Bessemer converter of the iron works for purifying the molten iron with formation of cyanogen compounds as described in U. S. Patent No. 1,505,281 by Adriaan Nagelvoort, dated Aug. 19, 1924, or for forming nitrogen compounds by any other suitable method such, for example, as those described in U. S. Patents 1,091,425, 1,120,682, and 1,174,944.

The ammonia soda process for the manufacture of sodium bicarbonate as at present carried out comprises the contacting of a gas mixture containing approximately 40% carbon dioxide and 60% nitrogen (or other inert gas) with an ammoniated brine solution in carbonating towers which results in a reaction between the carbon dioxide content of the gaseous mixture and the sodium chloride of the solution to form sodium bicarbonate and ammonia chloride. The sodium bicarbonate is commonly converted to the normal salt by heating as is well-known in the art.

It is the present practice in the operation of the ammonia soda process to calcine all or part of the sodium bicarbonate formed according to the following equation:

whereby additional carbon dioxide gas is obtained which is used to enrich the normal gas mixture as above described whereby under certain conditions the reacting gas mixture may eventually contain as high as 60%-75% of carbon dioxide even though the normal gas as received from the kilns and as used at the beginning of the operation contains as low as 35% carbon dioxide. It is also the practice in the manufacture of sodium bicarbonate by the ammonia soda process as now employed to pass the gases into the carbonating towers and force the same therethrough against the normal hydrostatic pressure prevailing in the towers which varies from 30 to 60 pounds per square inch, depending upon the height of the towers.

From the above it will be seen that the proportion of carbon dioxide in the gases as now generally used in the ammonia soda process is normally approximately 40%, which percentage is increased by enrichment to possibly as high as 60%-75%. In the waste gases obtained from blast furnaces after combustion of the carbon monoxid and hydrogen content thereof the carbon dioxide content would be normally 20%-24% which may be increased by enrichment as in the usual practice to from 40% to 60%. It will be understood from the above that the term normal carbon dioxide content of the gaseous mixture and equivalent expressions as used herein refer to the carbon dioxide content of the gas employed for form-

ing sodium bicarbonate before such gas has been enriched by the addition of carbon dioxide obtained by calcining the bicarbonate or from any other source.

I find that sodium bicarbonate can be readily produced by means of a lean gas mixture containing normally as low as 20%-24% carbon dioxide, such as is obtained by burning the waste blast furnace gases in a sufficient quantity of air to combine with the carbon monoxid and hydrogen content thereof. In order to effect the formation of sodium bicarbonate with a lean gas mixture containing, for example, 20%-24% carbon dioxide I propose to increase the pressure upon the gaseous mixture before passing it into the carbonating towers over that ordinarily employed by placing the same under a pressure of from 30 to 60 pounds per square inch in addition to the hydrostatic pressure in the carbonating towers. That is, the normal hydrostatic pressure in the carbonating towers under present operating conditions being from 30 to 60 pounds per square inch. I propose to practically double this pressure in order that when operating with a normal gas of 20% to 24% carbon dioxide the volume concentration of the carbon dioxide will be equivalent under the increased pressure to that of a normal gas of 40% to 50% carbon dioxide such as is now generally used in the manufacture of sodium bicarbonate. In specifying the pressures which I propose to employ in addition to the ordinary hydrostatic pressure of the carbonating towers it is to be understood that the present process is not to be restricted to the use of the exact pressures indicated above but that the pressures above noted are given as illustrative only, and that the same may be varied somewhat dependent upon conditions of operation, such, for example, as that in operating with towers of such height as would provide a hydrostatic pressure of 30 pounds per square inch it might be found desirable to use an additional pressure of as high as 70 pounds per square inch in order that the total pressure upon the gas entering the towers be as high as 100 pounds per square inch, as I have found that a lean gas mixture, containing from 20% to 24% carbon dioxide produces sodium bicarbonate efficiently and of a grade suitable for the usual commercial uses when operating under a total pressure (including the hydrostatic pressure in the towers) of from 90 to 110 pounds per square inch. In other words I propose to use such pressure in addition to the normal hydrostatic pressure in the towers as will give a weight of carbon dioxide per unit volume in the compressed gas which is substantially the same as the weight of carbon dioxide per unit volume now used in the most efficient practice. But I do not wish to limit myself

to the exact pressures specified above as under conceivable conditions very cheap power might warrant working at much higher pressures. If the gases are thus compressed and cooled before being passed into the carbonating towers the expansion of the gases in the carbonating towers will serve to cool the carbonating towers while the reaction is proceeding and thus simulate conditions under which sodium bicarbonate is formed by the ammonia soda process when using gases containing the relatively high carbon dioxide content now generally employed. In other words I propose to employ a gas mixture relatively lean in carbon dioxide such as normally contains approximately 20%-24% of carbon dioxide, and in order to facilitate the use of such gas mixture and insure the formation of sodium bicarbonate crystals of suitable size I place the gaseous mixture under a pressure substantially in excess of that necessary for overcoming the hydrostatic pressure in the carbonating towers. When the gases are thus placed under super-normal pressure before being admitted to the carbonating towers I prefer to cool the same after compression but before their admission to the towers in order that the partial expansion of the gases in the carbonating towers will act most efficiently to cool the towers. It will be understood in this connection that the relatively large nitrogen content of the gaseous mixture which I propose to employ will be compressed equally with the carbon dioxide content and that the nitrogen content of the mixture while chemically inactive in the ammonia-soda reaction will, by its expansion in the carbonating towers, participate in the cooling action.

While the gases may be permitted to expand somewhat in the carbonating towers in order to effect a cooling action counterbalancing to a certain extent the heat of reaction, I propose to maintain the carbonating towers under a considerable pressure in order to prevent a too rapid passage of the gas therethrough with consequent loss by reason of incomplete contact with the ammoniated brine, and prefer to pass the exit gas from the carbonating tower through a low pressure turbine to recover a portion of the power used in the initial compression of the gases.

It has been the practice heretofore to add the carbon dioxide obtained from the calcination of the sodium bicarbonate to the normal gas for the purpose of enriching the same by increasing the percentage of carbon dioxide therein and this practice may be followed in carrying out the process described herein or I may employ a series of carbonating towers and pass the gases rich in carbon dioxide, obtained by calcining the bicarbonate, through a tower containing

freshly prepared ammoniated brine to fix a certain proportion of the ammonia in the form of ammonium carbonate and then pass the normal lean gas therethrough, thus preventing undue loss of gaseous ammonia which would be more freely taken up by the large proportion of inert gas in the lean mixture.

The gas rich in carbon dioxide as obtained from calcining the sodium bicarbonate may be passed through a carbonating tower which is not under pressure, thereby avoiding the additional cost of compressing this rich gas to pressures in excess of the normal hydrostatic pressure in the carbonating towers. The partially carbonated ammoniated brine may then be passed into a carbonating tower which is under pressure and the lean gas mixture passed therethrough under a pressure in excess of the hydrostatic pressure in the tower as above described.

The gas remaining after the elimination of the carbon dioxide from the mixture in the carbonating towers consists almost entirely of nitrogen and this process affords the most economical means devised up to this time for producing large quantities of pure nitrogen for nitrogen fixation purposes. This results by reason of the enormous quantities of air employed in the operation of the modern blast furnace as well as from the relatively large proportion of nitrogen in the gases as they come from the stoves after the combustion of the carbon monoxide and hydrogen.

A large quantity of substantially pure nitrogen is thus rendered available for use by any desired fixation process whereby nitrogen compounds may be readily formed, and the cost of the nitrogen is made relatively low by reason of the fact that it is obtained from what are ordinarily waste products of the iron works. The process also possesses the added advantage of producing sodium bicarbonate in large quantities and at a relatively low price as an incident to the elimination of carbon dioxide from the nitrogen.

If the drawings annexed hereto there is shown a diagrammatic arrangement of one form of apparatus which may be employed in carrying out the process although it is to be understood that various different arrangements of the elements may be employed, and certain modifications of the same may be used as will be apparent to those skilled in the art.

Referring to the drawings 1 designates a supply pipe for conducting the exit gases from the blast furnace to a blower 2, it being understood that any desired arrangement of dust receptacles and scrubbers may be interposed between the blast furnace and the blower for traverse by the gases to eliminate therefrom dust and such other foreign material as it may be advisable to re-

move before burning the gases. 3 designates an air pipe through which air may be forced into the stoves or gas engines 5 by means of a suitable blower (not shown) in sufficient quantity to furnish a supply of oxygen for combining with the carbon monoxid and hydrogen content of the gases to secure complete combustion of these gases. From the blower 2 the gases from the blast furnace are forced through a pipe 4 into the stoves or heaters 5 where they are mixed with the air entering through the pipe 3 which provides the necessary oxygen for their combustion. The flow of air is preferably so regulated as to supply an amount of oxygen just sufficient to combine with the carbon monoxid and hydrogen to form carbon dioxid and water vapor respectively.

While the stoves or heaters 5 are shown as embodied in a single structure it is to be understood that there may be any desired number of such heat engines and that the terms stoves, heaters, etc., as applied thereto covers not only the usual direct burning gas heaters but also gas engines of any type which may be suitable and adapted for use in this connection.

From the stoves or gas burners 5 the gases pass through a pipe 6 to a scrubber 7 through which they may be passed for the purpose of cooling the gaseous mixture and removing any dust or other extraneous matter which may have been taken up in the gas burners. A gasometer 8 is shown as connected with the scrubber 7 by means of a connecting pipe 9 in order that a suitable supply of gases from the burner may be stored for use in the manufacture of sodium bicarbonate or for diverting the gaseous mixture from one to another of a series of carbonating towers 10 as may be desired in operation.

It is to be understood that a series of gasometers 8 may be employed instead of one only as shown in the drawings, the number being dependent upon the capacity as well as the volume of gases received from the gas burners and the number and capacity of the carbonating towers employed. The carbonating towers 10 as well as the gasometers 8 may be arranged in series as the rate of flow of the gases through the carbonating towers will ordinarily be somewhat slower than the rate of flow of the gases through the gas burners. In the present instance there has been shown a single gasometer 8 and a single carbonating tower 10 connected to the gasometer by a pipe 11, through a compressor 8', this showing of the arrangement of the parts by means of a single unit each being for the purpose of simplifying the arrangement of parts in the drawings, but it is to be understood that the invention comprehends the use of a plurality of gasometers and a plurality of carbonating towers together with such arrangement of connect-

ing pipes as permit the drawing of the gases from any one or more of the gasometers and their delivery to any one or more of the carbonating towers either singly or in series as circumstances may require or conditions of operation render expedient. While the blower 2 is shown for forcing the gases into the gasometer 8 from whence they may pass to the carbonating tower 10 by reason of the pressure normally exerted thereupon by the gasometer cover it is to be understood that I may employ any suitable number of compressors 8' for forcing the gases from the gasometer 8 through the carbonating tower 10 or for compressing the gases to a suitable degree before their entry into the carbonating tower.

In this connection it may be stated that in placing the gases from the gasometers 8 under compression in excess of that required to overcome the hydrostatic pressure in the carbonating towers I propose to install one or more compressors 8' between the gasometers 8 and the carbonating towers as well as suitable cooling coils or other similar devices for cooling the gases after compression and before admission into the carbonating towers. I also place a suitable gas turbine 12' between each carbonating tower 10 which is being operated under pressure in excess of the normal hydrostatic pressure of the tower whereby the gas leaving the carbonating tower under pressure will escape through the turbine in passing from the carbonating tower 10 to the gasometer 13, thus making it possible to recover a portion of the power used in compressing the gas. While for purposes of illustration a single gasometer 13 is shown as receiving the gases from the carbonating tower or towers through the pipe 12 it is to be understood that the invention comprehends the use of a plurality of gasometers for this purpose, especially as it may be desirable in practice to store gases from the carbonating towers for a longer or shorter period of time before utilizing the same in the fixation of nitrogen or for other purposes. When the gases (consisting principally of nitrogen) emerging from the carbonating tower or towers are used for the fixation of nitrogen either by the particular method shown herein or in any other suitable or desired manner it will probably be found desirable to employ a plurality of gasometers 13, each of which may advantageously be located in proximity to a single nitrogen fixation unit, or the several gasometers 13 may be so interconnected with one or more nitrogen fixation units that the gases may be drawn from any one or more of said gasometers and fed to any one or more of the nitrogen fixation units. In conducting the gases from the gasometer or gasometers 13 to the nitrogen fixation units it is regarded as desirable to interpose one or more

fans or blowers between the gasometer or gasometers and the unit or units being operated, the number as well as the capacity of the fans or blowers employed being dependent upon the number and capacity of the gasometers as well as the number and capacity of the nitrogen fixation units being operated and the arrangement of the connections for placing the units in communication with the gasometers. In the present instance a single blower 15 is shown which is adapted to draw the gases from the gasometer 13 through the pipe 16 to the nitrogen fixation unit 17. The nitrogen fixation unit illustrated diagrammatically herewith comprises a Bessemer converter, or modified Bessemer converter 18, provided with trunnions 19 mounted in bearings 20 carried by supporting standards 21. The pipe 16 communicates through one of the trunnions 19 with the tuyères in the base of the converter after a manner well-known in the art whereby the gases may be forced through the tuyères to pass through the molten metal in the converter after the manner described in United States Patent No. 1,505,281.

An air pipe 24 communicates through the other trunnion 19 with the tuyères at the base of the converter in a similar manner and in the operation of the nitrogen fixation unit shown it is proposed to first force a current of air from the pipe 24 through a mass of molten metal in the converter 18 by means of a blower (not shown) until the silicon content of the metal in the converter is substantially eliminated, and then discontinue the current of air through the pipe 24 and immediately pass a current of the nitrogen gas from the pipe 16 through the molten metal in the converter 18 to remove the carbon content of the molten metal and at the same time effect a union of the carbon and nitrogen in the presence of the heated metal acting to promote the reaction and to form cyanogen compounds which may be recovered and conducted by suitable means to a receptacle where they may be cooled and freed from impurities or converted into other forms. When necessary or desirable an alkali, alkali compound or other strongly basic element may be introduced into the molten metal contained in the converter during the passage of nitrogen gas therethrough or previous to the introduction of the nitrogen, and the basic element may be introduced into the metal in any desired manner such as that described in the copending application mentioned above. While the nitrogen fixation unit illustrated herewith has been shown and described as corresponding with that described and claimed in United States Patent No. 1,505,281, it is to be within the purview of the present invention to substitute for the nitrogen fixation unit herein de-

scribed any other suitable form of nitrogen fixation apparatus employing any other suitable process or mode of operation, such, for example, as those described and claimed in U. S. patents to Bucher 1,091,425, 1,120,682 or 1,174,944.

While I have shown diagrammatically one arrangement of apparatus capable of being utilized in carrying out the present invention it is to be understood that the form and arrangement of the apparatus illustrated herewith is shown solely for the purpose of illustration and that various modifications may be made therein both with respect to the arrangement of the parts, as well as in the form and method of connecting the elements without departing from the intended scope of the present invention.

It is also to be understood that certain or all of the elements shown may be multiplied if desired and various details of refinement introduced in the manner of connecting the parts as well as in the provision of suitable and adequate means for securing a proper flow of the gases therethrough while within the scope of the present invention and the claims appended hereto.

From the above it will be understood that I have provided a simple and readily operable method and means for obtaining large quantities of substantially pure nitrogen capable of use for the fixation of nitrogen in quantities adapted to make possible large scale production of nitrogen fixation products, such as has heretofore been impractical by reason of the comparatively limited quantities of nitrogen which have been made available by processes previously used, as well as the high cost of producing the same. It will be seen moreover that my improved process comprehends the production, as an incident to the purification of the nitrogen obtained, of large quantities of sodium bicarbonate at a cost substantially below that at which the same can be produced by the methods employed at the present time.

This application is a continuation in part of my application Serial Number 653,739, filed July 25, 1923.

What I claim is:—

1. The process for obtaining sodium bicarbonate and nitrogen which comprises, burning waste blast furnace gases in air to convert the carbon monoxide and hydrogen content thereof to carbon dioxide and water with proportionate increase in the nitrogen content, compressing the gaseous mixture thus formed and passing it into contact with ammoniated brine while under a pressure considerably in excess of the hydrostatic pressure exerted by the ammoniated brine.

2. The process for treating waste blast furnace gases which comprises, burning the gases in a quantity of air sufficient to oxidize the combustible elements thereof thereby

115

125

130

6 forming a gas mixture containing less than 30 per cent of carbon dioxide, washing the gaseous mixture thus formed to remove impurities therefrom, compressing the gases 5 and passing them into contact with ammoniated brine while under a pressure considerably in excess of the hydrostatic pressure exerted by the ammoniated brine to remove the carbon dioxide component of the 10 gases with formation of sodium bicarbonate.

3. The process for treating waste blast furnace gases which comprises, burning the gases in a quantity of air sufficient to convert the carbon monoxide content thereof to carbon dioxide and form a mixture containing less than 30 per cent of carbon dioxide, washing the gaseous mixture thus formed to remove impurities therefrom, compressing the gaseous mixture, cooling the said gases after 15 compression and passing them into contact with ammoniated brine while under a pressure considerably in excess of the hydrostatic pressure exerted by the ammoniated brine to remove the carbon dioxide content of the 20 gases with formation of sodium bicarbonate.

4. The process of forming sodium bicarbonate and nitrogen which comprises, treating an ammoniated brine solution with a 30 gaseous mixture of carbon dioxide and nitrogen which normally contains less than 30 per cent of carbon dioxide by first placing the gaseous mixture under a pressure considerably in excess of the hydrostatic pressure 35 exerted by the ammoniated brine and passing it upwardly through the ammoniated brine while under such excess pressure to form sodium bicarbonate and separate the carbon dioxide from the nitrogen.

40 5. The process of obtaining sodium bicarbonate and nitrogen which comprises, treating an ammoniated brine solution with a gaseous mixture of carbon dioxide and nitrogen normally containing less than 30 per cent 45 carbon dioxide by admitting the said gaseous mixture to the carbonating towers of an ammonia soda apparatus under a pressure considerably in excess of the hydrostatic pressure exerted by the solution in the carbonating 50 towers, whereby the carbon dioxide content of the gaseous mixture will substantially completely combine with the solution to form sodium bicarbonate while at the same time a portion of the exothermic heat 55 of reaction will be counteracted by the expanding gaseous mixture.

6. The process of obtaining sodium bicarbonate and nitrogen which comprises, forming a gaseous mixture of carbon dioxide and 60 nitrogen containing less than 30 per cent of carbon dioxide by volume, compressing said gaseous mixture, treating an ammoniated brine solution with said gaseous mixture by admitting said gaseous mixture to the carbonating towers of an ammonia-soda appara-

75 tus while under a pressure considerably in excess of the hydrostatic pressure exerted by the solution in the carbonating towers whereby the carbon dioxide content of the gaseous mixture will substantially completely combine with the solution to form sodium bicarbonate thus separating the carbon dioxide content of the gases from the nitrogen, and recovering the nitrogen gas from the carbonating towers.

7. The process of obtaining sodium bicarbonate and nitrogen which comprises, treating an ammoniated brine solution in carbonating towers with a gaseous mixture of carbon dioxide and nitrogen which normally 80 contains less than 30 per cent of carbon dioxide, by first placing the gaseous mixture under a pressure, in addition to the normal hydrostatic pressure in the carbonating towers, sufficient to give a weight of carbon dioxide 85 per unit volume of the compressed gas substantially the equivalent of the weight of carbon dioxide per unit volume of carbon dioxide in gas normally containing approximately 40 per cent carbon dioxide, and passing the compressed gas upwardly through the ammoniated brine while under pressure to form sodium bicarbonate and separate the carbon dioxide from the nitrogen.

8. The process of obtaining sodium bicarbonate and nitrogen which comprises, treating an ammoniated brine solution in carbonating towers with a gaseous mixture of carbon dioxide and nitrogen which normally contains less than 30 per cent of carbon dioxide by forcing the gaseous mixture into the carbonating towers under a pressure of approximately double the hydrostatic pressure at the base of the towers to form sodium bicarbonate and separate the carbon dioxide 95 from the nitrogen.

9. The process of obtaining sodium bicarbonate and nitrogen which comprises, first treating an ammoniated brine solution in carbonating towers with a gaseous mixture 100 containing over 70% of carbon dioxide, and then passing a gaseous mixture of carbon dioxide and nitrogen which normally contains less than 30 per cent of carbon dioxide through the carbonating towers and into contact with the ammoniated brine which has previously been treated with the gaseous mixture containing over 70 per cent of carbon dioxide under a pressure considerably in 110 excess of the hydrostatic pressure in the carbonating towers to form sodium bicarbonate and separate the carbon dioxide from the nitrogen.

10. The process of obtaining sodium bicarbonate and nitrogen which comprises, treating an ammoniated brine solution in carbonating towers with a gaseous mixture of carbon dioxide and nitrogen, the said mixture containing less than 30% of carbon dioxide by volume, by forcing the gaseous mix-

ture into the carbonating towers under a pressure considerably in excess of the hydrostatic pressure at the base of the towers, and passing the said gaseous mixture through the ammoniated brine while maintaining such pressure upon the carbonating towers as will insure the contacting of the carbon dioxid

with the ammoniated brine while under a pressure considerably in excess of normal atmospheric pressure.

In testimony whereof I have affixed my signature.
